US00D791916S

(12) **United States Design Patent** (10) **Patent No.:** **US D791,916 S**
Rose (45) **Date of Patent:** **** Jul. 11, 2017**

(54) **SPRAY GUN TRIGGER**

(71) Applicant: **Robert J. Rose**, Richmond, VA (US)

(72) Inventor: **Robert J. Rose**, Richmond, VA (US)

(73) Assignee: **Worthen Industries**, Nashua, NH (US)

(**) Term: **15 Years**

(21) Appl. No.: **29/566,443**

(22) Filed: **May 31, 2016**

(51) LOC (10) Cl. **23-01**

(52) U.S. Cl.

USPC **D23/226**

(57) **CLAIM**

The ornamental design for a spray gun trigger, as shown and described.

DESCRIPTION

FIG. 1 is a perspective front view of the spray gun trigger, which embodies my design;

FIG. 2 is a perspective rear view thereof;

FIG. 3 is a bottom view thereof;

FIG. 4 is a top view thereof;

FIG. 5 is a rear view thereof;

FIG. 6 is a front view thereof;

FIG. 7 is a left side view thereof;

FIG. 8 is a right side view thereof;

FIG. 9 is a perspective view thereof mounted on a spray gun; and,

FIG. 10 is a side view thereof mounted on a spray gun.
The broken lines in FIGS. 1-8 illustrate portions of the spray gun trigger that form no part of the claimed design. The broken lines on the spray gun trigger in FIGS. 9 and 10 illustrate portions that form no part of the claimed design; the broken line showing of the spray gun in FIGS. 9 and 10 illustrates the environment of the claimed design and forms no part thereof.

1 Claim, 4 Drawing Sheets
